(57) **CLAIM**

We claim the ornamental design for an earphone, as shown and described.

DESCRIPTION

FIG. 1 is a first perspective view of an earphone;
FIG. 2 is a second perspective view of the earphone;
FIG. 3 is a front elevational view of the earphone;
FIG. 4 is a rear elevational view of the earphone;
FIG. 5 is a top plan view of the earphone;
FIG. 6 is a bottom plan view of the earphone;
FIG. 7 is a left side elevational view of the earphone;
FIG. 8 is a right side elevational view of the earphone;
FIG. 9 is a sectional view of the earphone taken along line 9-9 of FIG. 3 with internal system omitted;
FIG. 10 is a sectional view of the earphone taken along line 10-10 of FIG. 8 with internal system omitted; and,
FIG. 11 is a sectional view of the earphone taken along line 11-11 of FIG. 8 with internal system omitted.
Portions of the drawings shown in broken lines form no part of the claimed design.

1 Claim, 11 Drawing Sheets
